UNITED STATES PATENT OFFICE.

JOHN A. DEMUTH, OF OBERLIN, OHIO.

WORKMAN'S TIME RECORDER.

Application filed April 6, 1920. Serial No. 371,669.

To all whom it may concern:

Be it known that I, JOHN A. DEMUTH, a citizen of the United States, residing at Oberlin, in the county of Lorain and State 5 of Ohio, have invented a certain new and useful Improvement in Workmen's Time Recorders, of which the following is a full, clear, and exact description, reference being had to the accompanying drawings.

10 This invention relates to an apparatus for recording the time of arrival and departure of workmen.

An object of the invention is the provision of a recorder which may be simple 15 in construction and use, and efficient in permitting rapid registration and in being very difficult to defraud. A more specific object is the provision of a record strip adapted to be advanced beneath a writing opening 20 with means for permitting an indication to be made on the record strip at some definite time, whereby prior and subsequent registrations may be readily distinguished and with no possibility of confusion between 25 the two. Still another object is the provision of a time controlled device within the recording apparatus arranged to advance the registration strip automatically and serve as an additional check against fraudulent time registration.

The above and other features and objects will be more fully hereinafter described. The essential characteristics of the invention are summarized in the claims.

35 In the drawings, Fig. 1 is a side elevation of a recording apparatus, showing in dotted lines the operating mechanism; Fig. 2 is a plan thereof; Fig. 3 is a fragmentary vertical section thru the casing of the apparatus showing means for perforating the record strip; Fig. 4 is a similar view showing the strip feeding mechanism; Fig. 5 is a side elevation of a modified form of apparatus showing mechanism for automatically 40 advancing the record strip; Fig. 6 is a plan thereof; Fig. 7 is a sectional view showing the arrangement of perforating means with respect to the record strip; and Fig. 8 is a detail of the ratchet connection between 45 the time mechanism and the feed rolls.

The recording devices shown are particularly adapted for use in the time recording system shown, described and claimed in my Patent #1,267,989 issued May 28, 1918.

50 Referring to Figs. 1 to 4 of the drawings, I have shown a writing box 10, preferably

substantially rectangular, and provided adjacent to one end with a paper strip supply roll 13 pivoted as at 14 in slots 15 in the sides of the box. The end of the strip 11 60 from the roll 13 is brought over a suitable platen 20 and beneath a slotted plate 21, supported near the top of the box, and is then conducted through feed rolls 22 and 23. A cover 25 may be provided for the box 65 hinged as at 26 and locked in closed position in any suitable manner. The cover is provided with an opening 24 above offset slots or writing openings 27 and 28 in the plate 21 above the platen 20; the opening 27 70 being of a size adapted to permit writing on the record strip a time code symbol (which may be read from a clock displaying different symbols at successive intervals, as described in my patent above referred to 75 and in my application filed April 23, 1918, Serial 230,344) and the employee's signature, while the opening 28 is adapted to permit writing a number which has been assigned 80 to such employee.

The strip feeding means comprises the rolls 22 and 23 between which the paper strip 11 is passed. These rolls are provided with roughened surfaces, for example by covering them with sand paper. They are 85 shown mounted rigidly on the shafts 45 and 46, the lower shaft 46 being supported in bearings in the sides of the box. The upper shaft 45 is preferably supported in the free ends of a frame 48 pivoted at 47 to the sides 90 of the box. A leaf spring 49 depending from the cover 25 may engage the frame 48 and thereby urge the upper roll 22 into engagement with the lower roll 23. The means shown for rotating the feed rolls to 95 advance the record strip comprises a ratchet wheel 60 rigidly mounted on the shaft 46 and adapted to be engaged by suitable pawl mechanism. A push pawl 62 is pivoted as at 63 on a slide bar 64 mounted in keepers 100 66 projecting from the inside wall of the box. A slot 67 is provided in the side of the box through which projects a pin 68 secured to the slide bar 64 and on which may be mounted an operating handle or 105 knob 69. A spring 70 may be secured to the bar 64 inside of the box in such a manner that the bar is constantly urged into a position with the pawl 62 disengaged, the handle 69 then being at one end of the slot 110 67. Movement of the handle to the other end of the slot moves the slide bar and car-

ries the pawl into engagement with the ratchet wheel and rotates the latter the distance of one tooth. Upon releasing the handle 69 the spring retracts the pawl and slide to the position shown in Fig. 4.

For the purpose of providing a line of demarcation between registrations made within and outside of definite hours such as the time for beginning and quitting work, I arrange means beyond the control of the registering employes for marking the record strip at any desired time. Such means may satisfactorily comprise devices for perforating the record strip as shown most clearly in Fig. 3. Preferably rigid with the platen 20 there is a depending bracket 30 supporting as by a cap screw 31 an electromagnet 32. The magnet may be of any desired type, the one shown having a horse-shoe frame 32 with coils 33 thereon. The armature is shown formed in the nature of a bell crank pivoted at 36 to ears 37 depending from the platen 20; the armature proper comprising the plate 38 secured to the vertical arm 35 of the bell crank and adapted to move toward and away from the poles 34 of the magnet. The horizontal arm 39 of the armature lever may be guided within a keeper 40 depending from the platen 20. At the end of the arm 39 is shown a cross arm 41 having a row of pins or perforating points 42 adapted to extend upwardly into registering openings 43 in the platen 20 and plate 21.

When the circuit through the magnet is closed the armature will be attracted and the arm 39 of the armature lever will move upwardly causing the pins 42 to perforate the strip 11 supported on the platen. Breaking of the circuit through the magnet will release the armature and its weight will restore the pins to the position shown in Fig. 3.

In the modification shown in Figs. 5 to 8, a timing mechanism is employed to advance the record strip mechanically at constant speed beneath the writing opening. The mechanism is otherwise quite similar to the embodiment previously described although the parts are somewhat differently arranged. In this modified form of apparatus there is shown a box 70 having a paper roll 71 mounted therein on a transverse shaft 72. The free end of the strip 76 from the roll 71 is threaded over a suitable platen 20 past guiding rollers 73 and between feed rollers 74 and 75, urged together by a leaf spring 78. A plate 77 having a single writing opening adapted to receive all the registration data is shown above the record strip and platen, although it will be understood an additional offset opening corresponding to the opening 28 in Fig. 2 may be provided if desired. A cover 80 is provided for the box 70 having a writing open-

ing 81 over the platen 20 and plate 77 to expose the writing slot in the latter. The strip perforating means including the series of pins 42 actuated by a magnet 32 may be the same as that illustrated in Fig. 3. 70

The feed roll 75 is connected with a timing mechanism 85 mounted in one side of the box 70 whereby the paper strip 71 may be feed continuously through the rolls 74 and 75. The timing mechanism 85 is provided with the usual frame 84, power spring 86 and gearing 87 and is connected to the shaft 79 of the roll 75 to rotate the same at such a speed that the advancement of the strip 76 while the signature is being 80 written is negligible. I may also use means for advancing the strip 71 manually.

One means of arranging the parts to provide a constant driving connection between the feed roll shaft 79 and the clock mechanism 85, and also permit the paper strip to be advanced manually is shown more particularly in Fig. 8. The shaft 79 is supported in the side walls of the box and carries loosely mounted thereon the ultimate driving gear 89 of the clock gearing 87, and has rigidly secured thereon the feed roll 75, the handle 88 and a ratchet wheel 93. The gear 89 has a sleeve 90, to which is secured an arm 91, with a pawl 92 thereon urged into engagement with the ratchet wheel 93. With this construction the feed roll 75 may be moved manually by rotating the knob 88, thus advancing the ratchet wheel 93 at a faster rate than its driving 100 pawl 92 is carried by the clock gear 89.

The magnet 32 may be energized at any desired time to cause the pins 42 to perforate the record strip. Thus in the apparatus shown in Figs. 1 to 4 the magnet 105 may be connected with an operable switch 90 which may be manually closed by a watchman or other attendant at any desired time, such as when the hour for beginning or quitting work arrives, while in the apparatus of Figs. 5 to 8 the magnet may be energized by the closing of a switch controlled by the timing mechanism 85 if desired or by a manually operable switch. Whether manually or automatically operated, the perforating of the record strip after the registration of the last employe who is actually 110 on time, prevents any employes arriving later, who may have fraudulently discovered and recorded the last on-time symbol, from 115 receiving credit for arriving on time. 120

In Figs. 3 and 7, the magnet is shown as connected by means of lead wires 96 to a contact switch 95 and battery 97. This switch may be located at a point remote from the register, to be operated only by an authorized person who may cause the perforations of the strip by closing this switch, whereupon the battery energizes the solenoids actuating the bell crank 35. 125 130

In use the recording apparatus shown in Figs. 1-4 may be placed at a convenient point where the employes are required to sign as they arrive. While the details in the 5 application of my apparatus are described in my patent above referred to form no part of this invention, it may be stated here, by way of explanation, that the workman records the symbol appearing on a clock 10 within view of the recording apparatus, such as the symbol "RG", which designates the correct time, and his name, such as "J. R. Smith", in the opening 27. The handle 69 is then actuated to advance the ratchet 15 wheel 60 to rotate it one tooth, thereby advancing the strip an amount equal to the width of the opening 27, thus bringing the symbol and signature under the plate 21 and on the same line with the opening 28. 20 The employee then writes in the latter opening his number such as "36", thus completing his registration. The next employee to register, after writing his name and symbol in the blank space on the strip within the 25 opening 27 advances the strip in the same manner to bring a blank portion of the strip beneath the opening 28 in which he inserts his number. Thus by the offsetting of the openings 27 and 28 and the requirement of 30 the employee's name and number to be entered in different slots when registering, the symbol denoting the time at which any employee arrived, is carried by him out of sight of the next registrant before the first completes his registration, thus preventing a 35 succeeding employee from copying illegitimately the symbol used by his predecessor. When the hour to begin or quit work arrives the strip is perforated by the means 40 above described, thereby precluding any late employee from successfully registering himself in any manner as being on time.

A further check may be provided by the addition of time controlled means for advancing the record strip. Since the strip is 45 advanced by such a mechanism at a constant speed, the position of any employee's registration on the strip may be computed from any point on the strip in terms of 50 time, and even though an employee should surreptitiously acquire knowledge of a symbol which was displayed at an earlier period and register the same, the relative position on the record strip of his registration 55 serves immediately to detect the fraud. Should the automatic mechanism not advance the record strip sufficiently to remove the signature of one employee before the 60 next is ready to sign, the knob 88 may be rotated to advance the strip manually a sufficient amount to present a blank space beneath the registering opening.

It will be understood that the registering apparatus is required to be used whenever 65 the employee enters or leaves. The used

portion of the record strip may be removed by an authorized attendant at desired intervals and turned over to the timekeeper, who is in possession of a key whereby the times represented by the various symbols may be 70 deciphered, and the data assembled and arranged in any desired manner. It will be understood, however, that the symbol clock may be omitted if desired and the checking features of the perforating means and the 75 automatic advancing of the strip used either alone or concomitantly. Such an arrangement may be desirable in establishments where the actual time of arrival or departure, if within prescribed hours, is immediate- 80 rial.

I claim:

1. In a time recorder, a casing having a writing opening, a platen beneath the opening, a record strip adapted to be progressed 85 over the platen to receive individual registration data and means beyond the control of the registrant for providing on the strip indicating means separating registrations made within and outside of working hours 90 by transverse perforation, and means inaccessible to the registrant for operating the said means.

2. In a time recorder comprising a casing, a record strip therein adapted to receive 95 successive registrations, means mounted within the casing below the record strip adapted to perforate the same between registrations of different character, said means being inoperable by the registrant. 100

3. In a time recording apparatus, a casing, a record roll supported therein, means for advancing the free end of said roll over a writing support, a magnet within the casing, and perforating means on the armature 105 thereof adapted when the magnet is energized to perforate the strip.

4. In a time recording apparatus, a casing having a writing surface, a record roll within the casing, means whereby the free 110 end of the roll may be advanced over said writing surface, a magnet within the casing, an armature therefor, means for perforating the strip and movable by the armature, and adapted when the magnet is energized to effect such perforations, means for energizing the magnet, and controlling means therefor located a distance from the casing and inaccessible to the registrant. 115

5. In a recording device having a writing 120 opening, a record strip extending beneath the opening, means for normally continuously advancing the strip automatically corresponding to the passage of time, and means whereby the strip may be manually advanced in the same direction, ahead of the normal amount, to allow the next registration to be made more quickly. 125

6. A combination, a casing, a record strip therein, a writing support beneath an open- 130

ing in the casing, means for automatically advancing said strip according to the passage of time over the writing support, means for accelerating said advancement in the same direction as the normal movement of the strip including a manually operated roll independently controlled, and means for marking the strip to indicate a definite time, said means being remote from and inaccessible to the registrant.

7. In a time recorder, the combination of a casing and record strip therein, and means for securing the record strip to allow it to receive successive registrations, means extending parallel with the registrations

adapted to punch a series of perforations into the strip between registrations, means for operating punch means and a controlling means therefor remote from the casing and inaccessible to a registrant at the casing, 20 whereby the perforations may separate the registrations prior to given time from those subsequent to given time.

In testimony whereof, I hereunto affix my signature.

JOHN A. DEMUTH.
